US00D824361S

(12) **United States Design Patent** (10) Patent No.: **US D824,361 S**
(45) Date of Patent: **** Jul. 31, 2018**

(54) **WIRELESS HEADSET COMMUNICATION DEVICE**

(71) Applicant: **LG ELECTRONICS INC.**, Seoul (KR)

(72) Inventors: **Soonhyun Park**, Seoul (KR); **Dongsoon Kim**, Seoul (KR); **Hyunchul Kim**, Seoul (KR); **Sunmin Lee**, Seoul (KR)

(73) Assignee: **LG ELECTRONICS INC.**, Seoul (KR)

(**) Term: **15 Years**

(21) Appl. No.: **35/503,414**

(22) Filed: **Jan. 20, 2017**

(80) **Hague Agreement Data**

Int. Filing Date: **Jan. 20, 2017**

Int. Reg. No.: **DM/095244**

Int. Reg. Date: **Jan. 20, 2017**

Int. Reg. Pub. Date: **Jul. 21, 2017**

(30) **Foreign Application Priority Data**

Jul. 29, 2016 (KR) 30-2016-0037390

(51) **LOC (11) Cl.** **14-01**

(52) **U.S. Cl.**

USPC **D14/205**

(57) **CLAIM**

The ornamental design for a wireless headset communication device, as shown and described.

DESCRIPTION

1. Wireless headset communication device

1.1 : Perspective

1.2 : Front

1.3 : Back

1.4 : Left

1.5 : Right

1.6 : Top

1.7 : Bottom

1.8 : Reference

Reproduction 1.8 is a reference view showing the wireless headset communication device in an alternate position.

1 Claim, 8 Drawing Sheets
